UNITED STATES PATENT OFFICE.

MABEL LAVINIA STEVENSON, OF NORTH VANCOUVER, BRITISH COLUMBIA, CANADA.

SLEEPING-BAG.

1,130,116.

Specification of Letters Patent. Patented Mar. 2, 1915.

Application filed March 23, 1914. Serial No. 826 715.

To all whom it may concern:

Be it known that I, MABEL LAVINIA STEVENSON, a subject of the King of England, residing at North Vancouver, in the 5 Province of British Columbia, Dominion of Canada, have invented certain new and useful Improvements in Sleeping-Bags, of which the following is a specification, reference being had to the accompanying drawings.

This invention relates to new and useful improvements in sleeping bags and more particularly to a bag of this character which is especially adapted for infants, and the 15 main object of the invention is to provide a sleeping bag which is formed in three sections, namely the base or mattress section, the cover section which is detachably connected to the mattress section, and a removable pillow detachably secured to one end of the mattress section.

Another object of the invention is the provision of a sleeping bag of the above character which will possess advantages in points 25 of efficiency and durability, is inexpensive to manufacture and, at the same time, is simple in construction and operation.

With the above and other objects in view, the invention consists in the novel features 30 of construction, combination and arrangement of parts as will be hereinafter referred to and more particularly pointed out in the specification and claim.

In the accompanying drawing forming a 35 part of this application, Figure 1 is a top plan view of a sleeping bag constructed in accordance with my invention, the cover thereof being shown in a partly removed position. Fig. 2 is a side elevation thereof, 40 parts being broken away and shown in section. Fig. 3 is an end elevation. Fig. 4 is a transverse sectional view taken on the line 4—4, Fig. 2; and Fig. 5 is a transverse sectional view taken on the line 5—5, Fig. 2.

In carrying out my invention, I provide 45 a mattress section which is generally indicated by the numeral 1, preferably formed of a lightweight wool material and covered upon the outer face thereof, with water- 50 proof sheeting which is indicated by the numeral 2, the edges of which are sewed to the mattress, as shown at 3. It will be noted that by providing this wrapper or water-proof sheeting upon the upper face of the mattress, the mattress may be readily 55 washed, when desired to keep the same in a

sanitary condition. The mattress itself may be of any well known construction and size, as to be of a suitable thickness to provide a comfortable rest for the body of the infant. 60 If so desired, this mattress may be positioned in any desired place, either in a crib, bed, or even placed upon the ground in any desired position.

The cover, which is indicated by the numeral 4, may be formed of any desirable material and is to be slightly larger than the mattress 1, so that when the same is secured thereto, the edges of the cover will drop down over and entirely cover the body of 70 the mattress. The longitudinal edges of the mattress are provided with suitable catch members, indicated by the numeral 5, which are adapted to be detachably engaged with the catch members 6, carried by the cover 4, 75 so as to securely retain the cover in position when placed over the mattress. The length of the cover is to be sufficient to cover the entire body of the occupant of the bag, up to the neck, allowing only the head to protrude beyond the end of the cover. 80

The detached end of the cover is retained in position about the neck of the occupant by means of a strap 7, the medial portion of which is sewed or otherwise secured to the 85 end of the mattress, while the ends thereof are tied around the occupant's neck, as indicated by the numeral 8. Removably secured to the open end of the bag and preferably secured to the end of the mattress, is 90 a pillow member, indicated by the numeral 9, the inner face of the pillow being substantially concaved, as indicated at 10 and provided therein with the sockets 11 which are adapted to be detachably engaged with the 95 catch members 12 carried by the end of the mattress, so that the pillow member 9 may be readily attached to or detached from the mattress. It is preferred to have the pillow 100 9 constructed of the same material as the mattress and to be of a size in comparison with the size of the mattress.

From the above description taken in connection with the accompanying drawing, it will be seen that I have provided a simple 105 and durable sleeping bag for infants, which is constructed of three detachably connected sections, whereby they may be readily taken apart and replaced by new ones, the mattress being provided with a water-proof covering, so that the same may be readily 110 cleansed and it will be apparent that the

cover member 4 may be removed and washed, when desired. It will also be apparent that the device as herein shown and described, is extremely simple in construction and can be manufactured at a comparatively low cost.

While I have shown and described the preferred form of my invention, it will be obvious that various changes in the details 10 of construction and in the proportions may be resorted to for successfully carrying my invention into practice, without sacrificing any of the novel features or departing from the scope of the appended claim.

15 Having thus described this invention, what I claim is:—

As a new article of manufacture, a sleeping bag for infants including an elongated mattress section having one extremity 20 curved transversely, a pillow member having one marginal portion disposed inwardly on a curvature complementary to the curvature

of the end of the mattress section, said curved wall of the pillow member and the curved end of the sleeping bag being provided with coacting means whereby the pillow member may be detachably engaged with the mattress section, anchoring members disposed along the opposite longitudinal walls of the mattress section, and an 30 elongated cover member provided along its longitudinal margins with members to detachably engage the anchoring members along the longitudinal walls of the mattress section whereby said cover member may be 35 entirely disengaged from the mattress section.

In testimony whereof I hereunto affix my signature in the presence of two witnesses.

MABEL LAVINIA STEVENSON.
